UNITED STATES PATENT OFFICE.

SUSANNA HOOK, OF BATTLE CREEK, MICHIGAN.

WASHBOARD ATTACHMENT.

1,153,081.

Specification of Letters Patent. Patented Sept. 7, 1915.

Application filed April 12, 1915. Serial No. 20,896.

To all whom it may concern:

Be it known that I, SUSANNA Hook, a citizen of the United States of America, residing at the city of Battle Creek, in the county of Calhoun and State of Michigan, have invented certain new and useful Improvements in Washboard Attachments, of which the following is a specification.

10 My invention relates to washboards, and more particularly to reversible washboards.

The object of my invention is to provide a washboard which may be reversed, end for end, as desired, thereby producing a rubbing surface of different degrees of roughness.

15 Furthermore the object of my invention is to provide a board reversed for use in either direction, having a removable top attachment which may be suitably attached 20 upon each end to prevent water or suds from coming in contact with the user's apparel.

Finally the object of my invention is to provide a washboard having a removable attachment which can be applied to either end and also having a rubbing surface which, when used in one direction provides a rough surface for such heavy articles as blankets and heavy clothing, while the other side 30 provides an approximately smooth surface for such articles as shirts, waists and all apparel made of delicate fabric which may be rubbed without danger of tearing off the buttons or destroying the fabric.

35 With the above and other objects in view my invention consists in the details of construction and in the arrangement and combination of parts as illustrated in the accompanying drawing forming a part of this 40 specification, and in which:

Figure 1 is an elevation of my improved washboard. Fig. 2 is a side view. Fig. 3 is a perspective view of the end attachment. Fig. 4 is a side view of one of the attaching clips. Fig. 5 is a plan view of the screws for securing the attachment to the washboard, and Fig. 6 is an end view (A. B) of the rubbing surface when in reversed position.

50 In the drawings 1—1 indicates the side bars which are made of wood, and 2 is an approximately corrugated rubbing surface suitably secured to each of the side bars. The rubbing surface is formed with a series 55 of transverse raised portions, 3—3, between which is a plain surface, as shown in Fig.

6. The construction of the rubbing plate provides a rubbing surface of a different degree of roughness when the washboard is reversed end for end. A plate, 4, having 60 sharpened end extensions 5—5 bent at right angles to the body portion 4 is secured on the side bars by forcing the sharp projections into the wood, of which the side bars are formed. The removable end attachment 65 is formed of a single sheet of zinc, tin, galvanized iron, of durable metal, having a side portion, 6, with a top piece, 7, bent at right angles to the side portion. The top portion also has a downwardly extending flange, 8, 70 which engages the end of the side bars. The attachment is secured to the washboard by first attaching the plate, 4, to the side bars, and the top attachment is then placed over the end of the side bars with the holes in 75 the body portion registering with the apertures in the plate, 4. I then insert a screw, 9, which is provided with an eye, 10, through the plate, whereby the top plate is held in a suitable position. The plate 4 may 80 also be secured to the side bars by means of the screw, 11, having a bent portion, 12, which is driven into the wood so that the end portion, 12, registers with the one of 85 the apertures in the plate 4. By thus securing the plate, 4, it prevents the same from becoming accidentally displaced or lost, which would be the result if the plate were only secured by means of the pointed projections, 5—5.

90 It is believed that the construction of my improved washboard and end attachment 95 may be readily understood from the foregoing description, it being noted that when it is desired to use the rough surface of the board the end attachment is secured to the end whereby the rubbing surface would be in the position as that disclosed in A Fig. 6, and when it is desired to wash a delicate fabric, the attachment is secured to the opposite end whereby the rubbing surface is in the position shown in the left portion of Fig. 6, B.

100 It can be readily seen that I thus provide a washboard with an attachment to prevent the suds or water from coming in contact with the user's apparel, and which may be easily and readily attached and used upon either end, as desired.

105 What I claim as new and desire to secure by Letters Patent is:

110 The combination with a reversible wash

board of a removable, detachable end protector, comprising a metal plate extending transversely the entire width of the board, having a top portion bent at right angles to a side piece, said top portion being formed with a downwardly extending flange, said side portion being provided with apertures at each end and means adapted to be inserted through said apertures in the

side portion for securing the detachment to 10 the board, as and for the purpose set forth. In testimony whereof I have affixed my signature in presence of two witnesses.

SUSANNA HOOK.
